(57) **CLAIM**

The ornamental design for lamp, as shown and described.

DESCRIPTION

FIG. 1 is a perspective view of a lamp.

FIG. 2 is front view thereof;

FIG. 3 is a rear view thereof;

FIG. 4 is a right side view thereof, the left side being a mirror image;

FIG. 5 is a top view thereof; and,

FIG. 6 is a bottom view thereof.

The broken lines shown in the drawings illustrate portions of the lamp that form no part of the claimed design.
